United States Patent Office

Des. 222,589
Patented Nov. 9, 1971

222,589

TABLE

Gardner Leaver, New York, N.Y., assignor to Steelcase Inc., Grand Rapids, Mich.

Filed June 22, 1970, Ser. No. 23,580

Term of patent 14 years

Int. Cl. D6—03

U.S. Cl. D33—14

FIG. 1

FIG. 2

FIG. 3

FIG. 4

FIG. 5.

FIG. 6.

FIG. 7.

FIG. 8.

FIG. 1 is a perspective view of a table showing my design;

FIG. 2 is a perspective view of the table;

FIG. 3 is a perspective view of a modified form of the table of FIG. 1;

FIG. 4 is another perspective view thereof;

FIG. 5 is a front view of the table of FIG. 1;

FIG. 6 is a side view thereof;

FIG. 7 is a front view of the table of FIG. 3; and

FIG. 8 is a side view thereof.

I claim:

The ornamental design for a table, substantially as shown.
